UNITED STATES PATENT OFFICE.

ROBERT R. RUST, OF NEW YORK, N. Y.

METAL-TWISTING MECHANISM.

Application filed October 11, 1919. Serial No. 329,893.

To all whom it may concern:

Be it known that I, ROBERT R. RUST, a citizen of the United States, a resident of the city of New York, county of Queens, and 5 State of New York, have invented new and useful Improvements in Metal-Twisting Mechanism, of which the following is a specification, reference being had to the accompanying drawings, in which—
10 Fig. 1 is a plan of mechanism embodying my invention; Fig. 2 is a side elevation thereof; Fig. 3 is a side elevation showing the pulling element in the act of engaging a metal plate; and Figs. 4 and 5 are details 15 of the pulling element.

My invention relates to apparatus for twisting metal, such as plates, bars or rods, and comprises a pulling element by which the metal may be drawn through a twisting 20 mechanism and twisted or distorted into the desired conformation. My invention also 25 consists in the features which I shall herein-
after describe and claim.

Referring to the drawings, the twisting 25 mechanism A which I prefer to employ, consists in a pair of rolls 2 which I have shown to be arranged on vertical axes, and a second pair of rolls 3 in advance of the rolls 2, which are rotatable through an angle of 20 30 to 30 degrees from the vertical about a horizontal axis.

The pulling mechanism B comprises a pair of parallel link belts 5 mounted on sprockets 6 secured on and driven by the 35 shafting 7 from any suitable source of power, such as C, and the pulling device 8, which consists in a base 9 bolted across the link belts 5, a pair of standards 10 mounted on the base 9, and a support 11 pivoted on 40 trunnions 12 which are positioned in the standards 10. The support 11 carries a rotatable T-shaped bolt 13 upon the outer end of which is secured a hook 14 and between the shoulder 15 and the support 11 is a 45 spring 16 which holds the head 17 of the bolt 13 against the roller bearings 18 in the support 11. The springs 19 which are mounted on the trunnions 12, bear against the base 9, at their inner ends and at their outer ends 50 against the arms 20 of the support 11 and thereby serve to return the support 11 and with it the bolt 13 to normal position, against the stop 21 on the base 9, at right angles to the link belts 5 when the hooks 14 are not en- 55 gaged.

In operation the metal to be twisted, which

I have shown in the form of a flat steel plate D, is cut into suitable lengths, punched at 22, and is fed into the rolls 2 and 3 both of which at first are arranged with vertical 60 axes. As the plate advances, the rollers 3 are rotated by the operator until their axes are at an angle usually from 20 to 30 degrees from the horizontal and are locked in that 65 position by the operator and remain in that position until the plate has passed there- through. By so manipulating the rollers 3 any desired degree of twist may be given to 70 the plate. When the plate projects in front of the rolls 3, one of the hooks 14 of the 75 pulling device 8 engages the eye 22 on the plate and pulls it forwardly through the rolls 2 and 3, and support 11 at the same time rotates about the trunnions 12 until its axis is parallel with the line of pull, as is 80 shown in Fig. 2. As the bolt 13 is also free to revolve upon the roller bearings 18 on the support 11, it rotates with the plate D as the plate is twisted by the rolls 2 and 3. When the metal has been pulled through the rolls 85 2 and 3, its weight is sufficient to cause the hook 14 to rotate into a downwardly facing position and thereby permit the strip D to drop free from the hook 14 and the pressure of the springs 19 against the arms restores 90 the bolt 13 to normal position against the stop 21.

The depending projection 21^a on the bottom of the bolt 13 has a bearing face for en- 95 gagement against a correspondingly shaped bearing face on the stop 21. These faces may be flat or of suitable complementary shape. After the strip D has dropped off the hook 14, leaving it in a downwardly fac- 100 ing position, the springs 19 force the pro- jection 21^a back against the stop 21, and if the bearing faces of the stop and projection are not then in bearing the pressure of the 105 springs 19 will cause the bolt to rotate until the bolt 13 and hook 14 assume the normal 110 position shown on the upper side of Fig. 2 and in Figs. 4 and 5, in which these faces are shown in parallel. In this position the support 11 and bolt 13 are carried around by the link belts into the position shown in Fig. 3, with the hook in position to engage the aperture 22 in a succeeding plate.

I have found that my invention is very ef- 115 fective and of great utility in pulling metal strips, bars or plates through twisting ma- chines.

The terms and expressions which I have

employed are used as terms of description and not of limitation, and I have no intention, in the use of such terms and expressions, of excluding any mechanical equivalents of the features shown and described, or portions thereof, but recognize that various structural modifications are possible within the scope of the invention claimed.

What I claim is:

- 10 1. In a metal twisting machine, a twisting element and a pulling element, the pulling element comprising a tractive member having mounted upon it a pivoted support, a rotatable shaft in said support and means on the shaft for engaging a metal blank and pulling it through the twisting element, the support traveling through a closed cycle, after disengagement from a metal blank, to return it to initial position, and means under the control of a spring for aligning the means on the rotatable shaft in position for engaging a succeeding metal blank.
- 20 2. In a metal twisting machine, a twisting element, and a pulling element, the pulling element comprising a tractive member having mounted upon it a coupling member for engaging and pulling a metal blank through the twisting element, said coupling member being capable of rotation about its own axis in the direction of the twist of the metal blank, the tractive member being mounted for movement in a closed cycle, and auto-

matic means for aligning the coupling member automatically to engage a succeeding metal blank and pull it through the twisting element.

3. In a metal twisting machine, a twisting element, and a pulling element, the pulling element comprising an endless power driven belt, a chair mounted on said belt, a support pivoted to said chair, a coupling member revolubly mounted in said support for engaging and pulling a metal blank through said twisting element, and spring controlled means for automatically aligning the coupling member in position to engage and pull a succeeding metal blank.

4. In a metal twisting machine, a twisting element and a pulling element having a coupling member for engaging a metal blank to be twisted and a tractive member for pulling the coupling member, the coupling member as it draws the metal through the twisting member being free to rotate with the metal blank about the axis of the latter, the coupling member being spring pressed against a portion of the pulling element after disengagement of the coupling member from the metal blank, whereby the coupling member is automatically returned to normal position ready to engage a succeeding blank.

ROBT. R. RUST.
